UNITED STATES PATENT OFFICE.

WILLIAM WEICKER, OF HERMSDORF, GERMANY, ASSIGNOR TO PORZELLANFABRIK KAHLA, FILIALE HERMSDORF KLOSTERLAUSNITZ, OF HERMSDORF, GERMANY.

INSULATOR.

992,462.

specification of Letters Patent. Patented May 16, 1911.

Application filed May 11, 1907. Serial No. 373,065.

To all whom it may concern:

Be it known that I, WILLIAM WEICKER, engineer, a subject of the German Empire, residing in Hermsdorf, Sachsen-Altenburg, 5 Germany, have invented certain new and useful Improvements in Insulators, of which the following is a specification.

The object of the present invention is to produce an insulator of high resistance that 10 will discharge the drops of water by electrostatic action and cause them to be discharged laterally instead of being attracted downward toward the lower portion of the insulator or its supports. This result is 15 effected by a special arrangement of the insulator whereby a very strong electrostatic field is produced for the purpose of causing the drops to fly outward. For this purpose the insulator is provided with a roof as 20 nearly flat as possible and formed of a good conductor preferably metal, that is in electrical connection with the wire. The roof cannot be horizontal as the water would not readily pass off therefrom, but it must be 25 comparatively flat in order to cause the drops to fly off in a nearly horizontal direction. The kinetic energy of the drops received by the electrostatic discharge is strong enough to overcome the attraction of 30 the supports in their passage outward, and are repelled from the supports so that they lose all their attraction therefor. The efficiency of such a roof can be increased by making a series of hoods or plates below the 35 top metal one, the electrostatic action of which will tend to repel the drops.

In the annexed drawings various forms of this invention are shown in which—

Figure 1 shows an insulator having three 40 separate hoods in connection with a comparatively flat roof of metal. Fig. 2 shows a similar arrangement with but two hoods. Fig. 3 shows another one with four hoods. Figs. 4, 5 and 6 show other forms of hoods 45 on the insulator. Figs. 7 and 8 show other forms of insulators with the metal roof.

In the device shown in Fig. 1, the insulator ^a has three hoods at its bottom portion and is provided with a metal roof ^b some- 50 what dish-shaped. The conductor ^L may engage a groove or bit ^c in the insulator at one side or it may lie in a groove ^d at the

top of the insulator. In both of these places the bare wire is in contact with the hood ^b.

In Fig. 2, the wire ^L is placed below the 55 hood ^b, but connected therewith by a conductor ^e.

In Fig. 3, the insulator ^a has but a single hood ¹, the insulator being otherwise similar to that of Fig. 2.

In Fig. 4 the insulator ^a has three hoods 60 ^{1, 2 and 3} diverging outward or conically-shaped.

Figs. 5 and 6 show a similar arrangement with but two hoods.

Fig. 7 shows the insulator of more nearly cylindrical shape and corrugated on the outside and carrying the metal hood ^b connected with the wire ^L by conductor ^e.

Fig. 8 shows a similar construction with a 70 single hood ¹.

In all of these constructions the insulator is provided with the comparatively flat metal roof that is in direct electrical connection with the conductor and hence will receive 75 an electrostatic charge. The drops falling from this roof will take a practically tangential direction outward at first by reason of being charged with the electrostatic energy, and hence will not be influenced by the 80 electrical attraction of the lower portion of the insulator.

Having thus described my invention, I claim:

1. An insulator for electric wires comprising a non-conducting portion and a metal roof secured thereto that is comparatively flat and is in electrical connection with the wire supported on the insulator.

2. An insulator for electric wires comprising a body portion of non-conducting material, a comparatively flat dome-shaped top or roof secured to the insulator and a conductor secured to the under face of the roof and adapted to connect with the conductor 95 that is to be supported by the insulator.

In witness whereof I have hereunto signed my name this 25th day of April 1907 in the presence of two subscribing witnesses.

WILLIAM WEICKER.
